AIR-VALVE FOR STOKERS

Filed Sept. 21, 1940

UNITED STATES PATENT OFFICE

2,340,281

AIR VALVE FOR STOKERS

Carl J. Winkler and Herman E. Winkler, Lebanon, Ind., assignors to U. S. Machine Corporation, Lebanon, Ind., a corporation of Indiana

Application September 21, 1940, Serial No. 357,690

9 Claims. (Cl. 110—72)

In the common form of small forced-draft stoker, it is customary to actuate simultaneously both the fuel-feeding mechanism and the blower which supplies the forced draft. One of the disadvantages met with in the operation of such a stoker arises from the sudden rush of air to the fire when the blower is started. In the first place, such a sudden rush of air may create a positive pressure within the fire box and thus expel obnoxious gases and finely divided or "fly" ash from the fire box through the fire door and other openings. In the second place, during intervals when the stoker is not operating, the fire burns down and may become so low that it will be extinguished by the sudden rush of air which occurs when the blower is started.

It is the primary object of our invention to employ a common control for the fuel-feeding means and the blower which provides the forced draft but, at the same time, to so regulate the flow of air to the stoker-retort that the supply of draft air will be built up gradually to its normal rate, thus eliminating a sudden blast of draft air and its consequent disadvantages as noted above. A further object of our invention is to control the quantity of air supplied to the fire under natural, or chimney, draft during periods in which the stoker is not operating. Still another object of our invention is to secure the results set forth by means of apparatus which can be economically manufactured and which can readily be installed in existing stokers.

In carrying out our invention in its preferred form, we mount in the air-supply conduit a valve secured to a shaft which extends outwardly through one wall of the conduit and which has secured to it one end of a spirally coiled bimetallic strip. The other end of this strip is anchored to a fixed point, and the strip is connected across the secondary of a transformer which is arranged to be energized simultaneously with an electric motor which operates the fuel-feeding mechanism and blower. The arrangement is such that when the bimetallic strip is cold the valve in the air supply conduit will be in or near closed position; but as the temperature of the bimetallic strip increases due to the passage of electric current through it it will rotate the valve-shaft and gradually open the valve, thus providing for a gradual increase in the supply of draft air and eliminating any sudden blast.

The accompanying drawing illustrates our invention: Fig. 1 is a vertical section on the line 1—1 of Fig. 2 illustrating the valve-controlling

bimetallic strip and its associated parts in elevation; Fig. 2 is a vertical transverse section on the line 2—2 of Fig. 1; Fig. 3 is a front elevation of the casing within which the device is enclosed; and Fig. 4 is a side elevation of a complete stoker illustrating the manner in which our draft-control is installed in association therewith.

Referring to Fig. 4, the common form of stoker embodies a hopper 10, fuel-feeding means shown as comprising a feed tube 11 and a screw-conveyor 12 mounted therein, a blower 13, and a conduit 14 for conveying air from the blower to the retort (not shown) into which fuel from the tube 11 is fed.

15 In embodying our invention in association with a stoker, we mount in the air conduit 14 a valve 15 which regulates the quantity of air supplied to the retort from the blower 13. Conveniently, this valve is a balanced butterfly valve secured to a shaft 16 which projects horizontally through one side wall of the conduit into a casing comprising a base 17 and a removable cover 18. The cover 18 is removably held in place, as by means of screws 20 which project through holes or slots 25 in the side walls of the cover and into ears 21 struck up from the casing-base 17. Within the casing 17—18, there is secured to the projecting end of the shaft 16 the inner end of a spirally coiled bimetallic strip 25, the outer end of which is secured to a bracket 26 mounted on a block 27 of electrical insulating material attached to the casing-base 17 in any convenient manner. A second bracket 28 on the block 27 is electrically connected to the inner end of the bimetallic strip 25 by a flexible electrical conductor 29. The conductor 29 is desirably in the form of a flat braided copper cable spirally coiled and, while sufficiently flexible to accommodate rotation of the shaft 16 through the opening and closing 30 movement of the valve 15, sufficiently rigid to insure that it will remain in spaced relation to the bimetallic strip 25.

The two brackets 26 and 28 are connected by wires 30 and 31 across the secondary of a step-down transformer 32. The primary of the transformer 32 is connected in parallel with a motor 33 which operates the blower 13 and the fuel-feeding screw 12, the transformer and motor being under the common control of a single switch 34. Usually, the switch 34 will be a temperature-responsive switch responsive to the temperature of a room which the furnace is to heat.

As it may be desired at times to subject the valve 15 to manual control, we form the outer 55 end of the shaft 16 into a crank 35 which projects

through an arcuate slot 36 in the front wall of the cover 18, such slot being long enough to permit the valve to rotate from fully open to fully closed position.

If desired, we may associate with the slot 36 adjustable abutments which limit the extent to which the valve 15 is opened or closed. The abutments illustrated in the drawing consist of ears 38 each of which is formed as the outwardly bent end of an arcuate strip 39 of sheet-metal, the body of such strip being provided with an arcuate slot 40 which receives a bolt 41 projecting through the front wall of the cover 18. The two ears 38 project through the slot 36 on opposite sides of the crank 35 and therefore limit movement of the crank and, correspondingly, of the valve 15. By loosening the bolts 41, the strips 39 can be adjusted to bring the ears 38 into any desired respective positions.

When the stoker is not operating to supply fuel to the retort, the switch 34 is opened and no current is flowing through the bimetallic strip 25. Accordingly, the temperature of the bimetallic strip is relatively low, and the valve 15 is closed. When the switch 34 is closed to operate the stoker, the transformer 32 is energized and current flows through the bimetallic strip 25. Under the heating effect of this current, the temperature of the bimetallic strip increases and gradually rotates the shaft 16 to move the valve 15 toward open position. As a result, there is no sudden blast of air into the fire box and the pressure therein remains sub-atmospheric because of the natural draft through the chimney. In consequence, obnoxious gases and fly ash are not blown from the furnace into the surrounding space where their presence would obviously be objectionable.

Under certain conditions, it may not be desirable to have the valve 15 completely closed during intervals in which the stoker is not operating. Thus, the normal intensity of the natural draft, the burning characteristics of the fuel used, the design of the heating plant, and the nature of the heating load may be such as to make necessary or desirable a limited opening of the valve 15 during intervals when the stoker is not in operation in order to prevent extinguishment of the fire from lack of air or to insure the existence of at least a certain minimum heating effect. Under these conditions, therefore, the strip 39 at the right-hand (Fig. 3) end of the slot 36 may be adjusted inwardly along the slot to any desired extent so that it will engage the crank 35 and prevent the bimetallic strip 25, when cold, from returning the valve 15 to completely closed position. The extent to which the valve opens when the bimetallic strip 25 is hot may be controlled by properly positioning the arcuate strip 39 at the opposite end of the slot 36.

In order to prevent the bimetallic strip from becoming unduly stressed when holding the valve in open position, it is desirable to provide the casing 17-18 with an opening for the admission of air so as to further the radiation of heat from the bimetallic strip. Conveniently, such an opening, indicated at 45, is provided in the bottom wall of the cover 18. The opening 45 may also provide for passage of the wires 30 and 31 by which current is supplied to the bimetallic strip, such wires being enclosed in a conduit 46 the end of which is secured through the medium of a suitable fitting 47 to a bracket 48 disposed within the casing above the opening 45.

The rate at which the bimetallic strip oper-

ates to open the valve 15 when the blower is started depends upon a number of factors such as the electrical resistance of the bimetallic strip, the voltage impressed upon it, the extent to which it will be distorted as the result of temperature changes, and the rate at which heat is radiated from it. By suitable selection of these factors, it is possible to vary widely the rate at which the valve 15 opens. We find it desirable in most instances to construct the device so that complete opening of the valve will not occur until from one-half to two minutes after operation of the blower has been started. Gradual opening of the valve during an interval of such extent will prevent the creation of positive pressures in the fire box and also will prevent the draft air from being supplied at a rate so high as might result in extinguishing a fire which has burned low during the preceding period in which the stoker was not operating.

We claim as our invention:

1. In combination with a stoker having a blower, fuel-feeding means, and a single electric motor for operating said blower and fuel-feeding means, a conduit for conveying draft air from said blower, a valve in said conduit, a shaft rotatable to move said valve between open and closed positions, a spirally coiled bimetallic strip having one end secured to said shaft and the other end secured to a fixed point, said strip being arranged to rotate said shaft and thereby move said valve toward open position as the temperature of the strip increases, and a transformer having its primary connected in parallel with said motor and its secondary permanently connected to the end of said strip, whereby whenever said motor is operating said strip will receive current causing it to become heated and to open said valve and maintain it open.
2. In combination with a stoker having a blower, fuel-feeding means, and a single electric motor for operating said blower and fuel-feeding means, a conduit for conveying draft air from said blower, a valve in said conduit, a shaft rotatable to move said valve between open and closed positions, a spirally coiled bimetallic strip having one end secured to said shaft and the other end secured to a fixed point, said strip being arranged to rotate said shaft and thereby move said valve toward open position as the temperature of the strip increases and capable of being heated by an electric current passing through it to a temperature at which it will move said valve to and maintain it in open position, and means for controlling the supply of electric current simultaneously to said motor and to said strip, whereby whenever said motor is operating said strip will receive current causing it to become heated and to open said valve and maintain it open.
3. In combination with a stoker having a blower, fuel-feeding means, and means including an electric motor for jointly operating said blower and fuel-feeding means, a conduit for conveying draft air from said blower, a valve in said conduit, a shaft rotatable to move said valve between open and closed positions, a spirally coiled bimetallic strip having one end secured to said shaft and the other end secured to a fixed point, said strip being arranged to rotate said shaft and thereby move said valve toward open position as the temperature of the strip increases and capable of being heated by an electric current passing through it to a temperature at which it will move said valve to and maintain it in open po-

sition, and a means for controlling the supply of electric current simultaneously to said motor and to said strip, whereby whenever said motor is operating said strip will receive current causing it to become heated and to open said valve and maintain it open.

4. The invention set forth in claim 3 with the addition of an adjustable stop for limiting closing movement of said valve.

5. A device for supplying draft air to a stoker, comprising a blower, an electric motor for operating said blower, a conduit for conveying draft air from said blower, a valve in said conduit, a shaft rotatable to move said valve between open and closed positions, a spirally coiled bimetallic strip having one end secured to said shaft and the other end secured to a fixed point, said strip being arranged to rotate said shaft and thereby move said valve toward open position as the temperature of the strip increases and capable of being heated by an electric current passing through it to a temperature at which it will move said valve to and maintain it in open position, and a means for controlling the supply of electric current simultaneously to said motor 25 and to said strip, whereby whenever said motor

is operating said strip will receive current causing it to become heated and to open said valve and maintain it open.

6. The invention set forth in claim 5 with the addition of an adjustable stop for limiting closing movement of said valve.

7. The invention set forth in claim 5 with the addition of adjustable stops for limiting opening and closing movements of said valve.

8. The invention set forth in claim 5 with the addition of a casing enclosing said strip, one wall of said casing having an arcuate slot concentric with said shaft, said shaft being provided with a crank projecting outwardly through said slot, and stops disposed in said slot on opposite sides of said crank and adjustable along said slot to limit opening and closing movements of said valve.

9. The invention set forth in claim 5 with the addition of a casing enclosing said strip, one wall of said casing having an arcuate slot concentric with said shaft, said shaft being provided with a crank projecting outwardly through said slot.
